UNITED STATES PATENT OFFICE.

HARRY F. CAVANAUGH AND ALFRED DORAN, OF OAKLAND, CALIFORNIA.

PORTABLE DISH-WASHER.

1,315,181.

Specification of Letters Patent.

Patented Sept. 2, 1919.

Application filed June 13, 1918. Serial No. 239,869.

To all whom it may concern:

Be it known that we, HARRY F. CAVANAUGH and ALFRED DORAN, citizens of the United States, residing at Oakland, in the 5 county of Alameda and State of California, have invented new and useful Improvements in Portable Dish-Washers, of which the following is a specification.

This invention relates to a dish washing 10 machine, and particularly to a machine of the portable type.

One of the objects of the present invention is to provide a simple and easily operated dish washing machine which is 15 adapted for use in hotels, restaurants and like purposes where dishes are to be washed hurriedly and in large quantities, and particularly to provide a portable machine which can be quickly and readily moved 20 from one tank or receptacle to another and which may be placed in any suitable receptacle whether round, square or otherwise shaped. Another object of the invention is to provide a water-tight casing for the 25 washing machine to permit it to be practically submerged when placed in a dish washing receptacle. Another object of the invention is to provide a propeller for circulating and driving the wash water through the 30 dishes in the receptacle; also to provide a permanent mounting for said propeller and an electric motor which may be connected with, or disconnected from, the propeller at will. Another object of the invention is to 35 provide means for guiding the water discharging from the propeller so that a jet-like effect may be obtained and also to provide a plurality of return passages for the water which deliver the water to the rear 40 side of the propeller. Further objects will hereinafter appear.

The invention consists of the parts and the construction, combination and arrangement of parts as hereinafter more fully described and claimed, having reference to the 45 accompanying drawings in which—

Figure 1 is a central, vertical section through the dish washing machine.

Fig. 2 is a cross section in plan view 50 taken on the line 2—2 of Fig. 1.

Fig. 3 is a vertical cross section on a reduced scale, taken on line 3—3 of Fig. 1.

Referring to the drawings in detail, A indicates in general a casing which consists 55 of a rear section 2, a front section 3, side sections 4 and a bottom section 5. Formed

in the forward section of the casing is a circular recess 6 and communicating with the inner end of said recess are a plurality of passages 7. Formed integral with the inner 60 wall 8 of the recess, or suitably secured thereto, is a bearing member 9 in which is journaled a shaft 10. Secured on the outer end of said shaft is a propeller 11 of suitable construction and secured on the inner 65 end of the shaft within the casing is a flexible coupling member 12 of the universal type.

This coupling consists of a disk in which is formed a cross slot 12^a and power is transmitted through the coupling in a manner 70 hereinafter to be described.

Forming a cover for the recess 6 is a screen 13 and carried by the outer end of the bearing member 9 is a stuffing box 14 which 75 prevents water from leaking through the bearing into the casing. Loosely mounted within the casing is an angle iron frame which consists of an upper section 15 and a lower section 16. Supported by the upper 80 section is an electric motor 17 and supported by the lower section is a bearing member 18 in which is journaled a shaft 19. Secured on one end of said shaft is a pulley 20 and secured on the opposite end of the 85 shaft is a coupling member 21 which co-operates with the disk 12 previously described, that is, the coupling member 21 is provided with a projecting tongue 22 which is adapted to enter the slot 12^a of the opposite coupling member. Power is transmitted to rotate the shaft 19 and the co-operating connected members by means of a belt 23 which is driven by a pulley 24 secured on the motor shaft. 95

In actual operation, if it is desired to wash a considerable quantity of dishes it is only necessary to place the same in wire baskets or like receptacles which may be placed in a tank of hot water. The dish 100 washing machine generally shown in Figs. 1 and 2 is then also placed in a tank in any convenient position. A circuit through the motor is then established and power is thus transmitted to drive the propeller 11 at a 105 comparatively high speed. The revolutions of the propeller cause suction within the recess 6 which draws water through the sides of the casing or the passages 7, this water when entering being immediately expelled through the screen 13 in a forward direction. Water is in this manner circu- 110

lated at a high velocity and as stream or jet action is obtained by the propeller, it can readily be seen that the water will be forced through the dishes at such a velocity that they will be rapidly rinsed or cleaned. The washing machine may be moved about the tank to direct the water as desired, or the baskets containing the dishes may be turned so that the water may enter from different angles.

A dish washing machine constructed as here shown has many advantages. First, the size or shape of the tank in which it is placed while the washing operation is taking place makes very little difference; secondly, it may be moved from one tank to another, for instance, it may be placed in a washing tank containing soap water and may afterward be placed in a rinsing tank. Third, it is so simple that nothing can get out of order and if it is desired at any time to take up slack in the driving belt or to lubricate the bearings it is only necessary to lift out the angle iron frame as this sits loosely within the casing. This angle frame is entirely open when lifted out of the casing, thus permitting the belt to be readily adjusted and the motor and bearing 19 to be lubricated whenever desired. Fourth, the construction of the universal coupling comprising the disks 12 and 21 is also of importance as either may be connected when the angle iron frame is reinserted by merely turning the propeller until the slot 12^a alines with the projection 22 and disk 21, that is, both coupling sections are moved into vertical alinement when the parts are reassembled or replaced within the casing, thus permitting the coupling to be quickly connected with comparatively little effort. Fifth, the provision of the screen 13 prevents food particles, dish rags or any like objects from entering the propeller, thus guarding it against damage, and the provision of the passages 7 permits an ideal circulation of the wash water as the forward opening allows the water to freely discharge while the passages 7 permit an ideal return of the water.

The motor employed in the present instance is comparatively small, actual practice having proven that 1/15th H. P. is more than sufficient. It is therefore unnecessary to employ a rheostatic switch and the circuit through the motor can therefore be established by an ordinary lighting switch or like device not here shown. Similarly a cover for the casing may be provided through which the wires extend that connect with the motor, this being generally indicated at B. The materials and finish of the several parts of the dish washing machine may be such as the experience and judgment of the manufacturer may dictate.

We wish it understood that various changes in the form, proportions and minor

details of construction may be resorted to within the scope of the appended claims, and that we do not wish to limit ourselves to the specific design and construction here shown.

Having thus described our invention, what we claim and desire to secure by Letters Patent is: —

1. A dish washing machine comprising a casing having a cylindrical recess formed in its forward face, a journal member carried by the casing centrally positioned with relation to said recess, a shaft mounted on said journal member, a propeller on said shaft within the recess, a bearing member within the casing in alinement with the first-named bearing member, a shaft journaled in said last-named bearing member, a flexible coupling connecting the propeller shaft with the last-named shaft, an electric motor within the casing, and a belt drive connection between the motor and the shaft within the casing.

2. A dish washing machine comprising a casing having a cylindrical recess formed in its forward face, a journal member carried by the casing centrally positioned with relation to said recess, a shaft mounted on said journal member, a propeller on said shaft within the recess, means within the casing for driving the propeller and a plurality of passages in the casing communicating at one end with the exterior of the casing and at their opposite ends with the interior of the cylindrical recess.

3. In a dish washing machine, a watertight casing, a propeller permanently journaled in the casing exterior thereof, a driving connection on the interior side of the casing, a motor within the casing, means for transmitting power from the motor to the driving connection, a recess in the casing forming a housing around the propeller, said recess having a forward central discharge opening and a plurality of passages formed in the casing communicating at their inner ends with the recess and at their outer ends with the exterior of the casing.

4. In a dish washing machine, a watertight casing, a cylindrical recess formed in the forward face of said casing, a propeller within said recess permanently journaled in the casing, a removable frame within the casing, a motor carried by said frame, a journal member carried by said frame, a shaft in said journal member, means for transmitting power from the motor to rotate said shaft and means for transmitting power from said shaft to drive the propeller.

5. In a dish washing machine, a watertight casing, a cylindrical recess formed in the forward face of said casing, a propeller within said recess permanently journaled in the casing, a removable frame within the casing, a motor carried by said frame, a

journal member carried by said frame, a shaft in said journal member, means for transmitting power from the motor to rotate said shaft, means for transmitting power from said shaft to drive the propeller, said means comprising a universal coupling, a plurality of passages formed in the casing communicating at their outer ends with the exterior of the casing and at their opposite ends with the interior of the recess, said recess having a central forward opening and a screen covering for said opening.

6. A dish washing machine comprising a water-tight casing, a propeller permanently

journalized in said casing, a removable frame 15 within the casing, an electric motor carried by said frame, and a driving coupling carried by the frame adapted to be connected with, or disconnected from, the propeller when the frame is removed or inserted. 20

In testimony whereof we have hereunto set our hands in the presence of two subscribing witnesses.
